AUTOMATICALLY RELEASING WING TIP FLARE BRACKET

Filed April 18, 1922

Inventor
Herbert O'Russell
Charles Leigh Paulus

By Robert N Young Atty.

UNITED STATES PATENT OFFICE.

HERBERT O. RUSSELL, OF DETROIT, MICHIGAN, AND CHARLES LEIGH PAULUS, OF DAYTON, OHIO.

AUTOMATICALLY-RELEASING WING-TIP FLARE BRACKET.

Application filed April 18, 1922. Serial No. 555,402.

To all whom it may concern:

Be it known that we, HERBERT O. RUSSELL and CHARLES LEIGH PAULUS, citizens of the United States, residing, respectively, at Detroit and Dayton, in the counties of Wayne and Montgomery and States of Michigan and Ohio, have invented certain new and useful Improvements in Automatically-Releasing Wing-Tip Flare Brackets, of which the following is a specification.

This invention relates to a flare bracket assembly intended to replace and improve upon the Holt wing tip flare bracket.

The object of the invention is to provide means for releasing and positively ejecting the flare automatically in case of a bad landing or crash at night when the flare is lighted.

A further object in view is to provide means for locking the movable parts of the device in their operative positions, holding them in such position until the flare is ejected by contact of the trip arm with the ground, after which the device is adapted to swing upwardly so as not to be injured with further contact with the ground.

With the above and other objects in view the invention consists in the novel construction, combination and arrangement herein fully described, illustrated and claimed.

In the accompanying drawings:

Figure 1 is a rear elevation of the flare bracket assembly.

Figure 2 is a side elevation thereof, partly in section.

The flare bracket assembly comprises an attaching bracket proper 1 having connected thereto by a pivot 2, a normal vertical depending flare carrying arm 3. The arm 3 has fixedly attached to the lower end thereof a flare candle housing 4 attached to receive one end of a flare candle 5, the latter being held in place by a clamping band 6 having end portions 7, which receive a clamping bolt 8 having a winged adjusting nut 9 on one end thereof, and trip lever 10 with a clamping face 11 engaging another clamping face 12 on one of the clamping band ends 7. The trip arm 10 extends below the lower end of the candle 5 so as to strike the ground, thus releasing the candle 5 which is thrown away from the machine by action of the

spring 15. The usual terminals 17 and 18 are provided on arm 3 for frictionally holding the wires with which such flare candles are provided for purposes of their ignition. A thrust member, or rod, 13 extends from the housing 4 upwardly to the bracket 1 to which it is connected by a pivot 14. The pivots 2 and 14 are off set from each other as shown in Figure 1 to enable the thrust member 13 to function. A compression spring 15 is contained in the housing 4 and when the candle 5 is in place, said spring 15 is compressed between the end of the candle and a slideable locking member 16 of tubular formation which surrounds the adjacent end of the thrust member 13, and is fixed thereto so as to slide in the opening in the top of housing 4 as the arms 3 and 13 move rearwardly. While the candle 5 is being carried by the flare bracket the spring 15 is compressed and therefore the whole assembly is held in the vertical operative position shown in the drawings. As soon, however, as the candle 5 is ejected, the spring 15 being allowed to expand, relieves the pressure on the sliding member 16 and this relieves the end pressure on the thrust member 13. This leaves the whole assembly free to spring upwardly in case it strikes the ground, thereby preventing injury to the mechanism. In other words the flare bracket assembly is permitted to yield upwardly freely only after the flare has been ejected.

What we claim is:

1. A wing tip flare bracket comprising an attaching bracket proper, a flare carrying arm pivotally attached to said bracket, a flare candle housing at the free end of said arm, candle clamping means on said housing, a trip arm to release said clamping means, a thrust member extending from said housing and pivotally attached to said bracket, a candle ejecting spring in said housing, said spring, flare carrying arm and thrust member acting when the spring is compressed to maintain the whole in operative position.

2. A wing tip flare bracket comprising an attaching bracket proper, a flare carrying arm pivotally attached to said bracket, a flare candle housing rigid with the free end of said arm, candle clamping means on said

2
housing, a trip arm to release said clamping means, a thrust member movably engaging said housing and pivotally attached to said bracket, a candle ejecting spring in said housing, said spring, flare carrying arm and thrust member acting when the spring is compressed to maintain the whole in oper-

ative position and permitting the whole to swing upwardly freely when said spring is relieved of compression.

10 In testimony whereof we affix our signatures.

HERBERT O. RUSSELL.
CHARLES LEIGH PAULUS.
